UNITED STATES PATENT OFFICE.

WILLIAM BEAUMONT, OF GRANITE, OKLAHOMA TERRITORY.

ROTARY ENGINE.

SPECIFICATION forming part of Letters Patent No. 774,551, dated November 8, 1904.

Application filed June 27, 1904. Serial No. 214,307. (No model.)

To all whom it may concern:

Be it known that I, WILLIAM BEAUMONT, a citizen of the United States, and a resident of Granite, in the county of Greer and Territory 5 of Oklahoma, have invented a new and Improved Rotary Engine, of which the following is a full, clear, and exact description.

This invention relates to improvements in rotary engines, an object being to provide an 10 engine of this type so constructed as to be evenly balanced while running and which may be operated with an economical use of steam.

Further objects of the invention will appear in the general description.

15 I will describe a rotary engine embodying my invention and then point out the novel features in the appended claims.

Reference is to be had to the accompanying drawings, forming a part of this specification, 20 in which similar characters of reference indicate corresponding parts in all the figures.

Figure 1 is a plan view, partly in section, of a rotary engine embodying my invention. Fig. 2 is a section on the line 22 of Fig. 1. Fig. 25 3 is a section on the line 33 of Fig. 1. Fig. 4 is a detail view of a valve mechanism employed. Figs. 5 and 6 are views, one in perspective and the other in side elevation, of portions of the valve mechanism; and Figs. 7 and 8 are trans- 30 verse sections of the valve mechanism, showing the parts in different positions.

Referring to the drawings, 5 designates a cylinder in which a piston-like disk 6 is mounted to rotate, and supported on the cylinder 5 35 is an abutment-cylinder 7. This cylinder 7 communicates with the cylinder 5, and through an opening forming this communication a portion of the abutment-disk 8 extends. It will be noted that the piston and abutment-disk 40 have their planes arranged at right angles to each other. The piston-disk 6 is somewhat smaller than the interior of the cylinder 5, so as to form a steam-chamber around the piston-disk. It is provided, however, at one 45 point with a piston-wing 9, which engages closely against the interior of the cylinder.

Seated in interior channels formed in the walls of the piston-cylinder and engaging with the sides of the piston-disk 6 are tubu-

lar packing-rings 10, and steam is admitted 50 to the rear sides of these rings through ports 11, so as to press the rings sufficiently tight against the piston. It will be noted that the piston-disk is transversely curved, so as to correspond with the peripheral curvature of 55 the abutment-disk, and the abutment-disk at one point is provided with an opening 12, which when coincident with the wing 9 will permit the wing to pass. Then by continued movement of the abutment-disk its periphery 60 will be engaged by the periphery of the piston-disk until the opening 12 and the wing 9 are again coincident.

Formed in the walls of the cylinder 7 at opposite sides of the abutment-disk are steam-chambers 13, to which steam is admitted 65 through a port 14, the chambers of a side communicating through a port 13^a. Each pair of chambers 13 has an area equal to the area of the wing 9, so that the pressure of 70 steam in the chamber at the opposite side of the piston-wing in which the piston is rotated will balance the pressure practically to force the abutment-disk toward the line of movement of the wing, and therefore relieve it 75 somewhat of frictional engagement with the wall of the cylinder.

Secured to the front side of the cylinder 5 is a casing 15, at one end of which is a steam-chest 16, receiving steam through a pipe 17. 80 Fixedly secured in the casing 15 is a valve-seat 18, having at its inner end a longitudinal and tapered opening to receive a correspondingly-shaped tubular valve 19. This valve has ports 20, providing communication 85 between its interior and the steam-chest 16, and extended outward from the valve, through a stuffing-box 21, is a stem 22, having on its outer end a gear-wheel 23, meshing with a gear-wheel 24, which in turn engages with a 90 gear-wheel 25, mounted on a counter-shaft 26, on the inner end of which is a bevel-pinion 27 for engaging with a bevel-pinion 28 on the shaft of the abutment-disk 8, the said shaft having a bearing in a block 28^a, adjustable 95 vertically by means of a screw 28^b. This gear-wheel 24 also engages with a gear-wheel 29 on the shaft of the piston-disk 6. By this

system of gearing the several rotary parts will be properly timed to perform their different functions.

For the purpose of adjusting the valve 19 5 to compensate for wear I employ a screw 30, which passes longitudinally through the valve-seat 18 and engages with the inner end of the valve. By manipulating the screw 30 and the stem 22 the valve may be quickly adjusted. Mounted to move longitudinally on 10 the valve-seat 18 is a regulating-sleeve 31. This sleeve is provided with a longitudinal interior channel 32, which receives a rib 33 on the exterior of the valve-seat, which permits the regulating-sleeve to move longitudinally, as before mentioned, but will prevent 15 rotary movement thereof. The valve-seat 18 has a port 34, which extends partially around it, and on opposite sides of a bridge piece or 20 block 35, which form the end walls of the port 34, stop-blocks 36 37 are movable. The stop-blocks have outwardly-extended pins or lugs which engage in channels 34^a, formed in the interior of the sleeve 31. For a portion 25 of their length at opposite sides the channels 34^a have straight walls or walls parallel with the axis of the sleeve. The other portions, however, have a spiral trend, so that when these spiral portions engage with the lugs of 30 the blocks 36 one of said blocks will be moved around the port 34, so that steam may pass through a port 39, formed in the valve into said port 34. It will be understood that only one block 36 or 37 is to be moved—that is, 35 depending upon the direction in which the engine is running. In Fig. 7 the blocks are in such a position as to permit a practically full head of steam to pass into the engine. In Fig. 8, however, the block 36 is shown as 40 turned to a position so that steam will be admitted to the engine only until the port 39 shall have reached the block 36.

The sleeve 31 is provided with a port 40, and steam passing through this port 40 into 45 a steam-chamber 41 in the casing 15 will pass through either one of the ports 42 43, which lead into the cylinder 5 at opposite sides of the piston-wing 9. As steam passes through the port 42, for instance, it will rotate the 50 piston in one direction and the exhaust will pass out through the port 43.

As a means for shifting the sleeve 31 I employ a lever 44, arranged at one end of the casing 15 and having a rod connection 45 with the sleeve. The lever may be held as adjusted by any suitable rack mechanism.

As a means for changing the direction of rotation of the engine I employ a slide-valve 46, movable in a slideway 47 forward of the 60 ports 42 43, and this slide-valve has a port 48 designed to direct steam from the chamber 41 into the port 42, and it also has a port 49 for directing steam into the port 43. The slide-valve is also provided adjacent to the ports 65 48 49 with exhaust-ports 50 51, designed, re-

spectively, to be placed in communication with the ports 42 43. As the valve is located in Fig. 1, live steam will pass through the port 42 and exhaust will take place through the port 43. The reversing-valve is shifted by 70 means of a lever 52, having a rod connection 53 with the valve.

It will be noted that the body of the engine is cast in four parts, A B C D, suitably bolted together, and is therefore comparatively 75 cheap to manufacture and assemble and is easily trued or turned up. In other words, the body of the engine is cast in four vertically-divided parts, so that the cylinder-cavity may be first bored out, while the parts C 80 D are bolted together until the cavity is true, then taken apart, and the other parts, A B, are similarly treated for the reception of the abutment-disk. This I consider important, as it is very difficult to secure proper adjustment 85 in any other way.

Having thus described my invention, I claim as new and desire to secure by Letters Patent—

1. A rotary engine comprising a piston-disk cylinder having interior annular channels, tubular packing-rings in said channels, steam-ports leading to the rear sides of the rings, and a piston-disk mounted to rotate in the cylinder and against the sides of which said rings press. 95

2. A rotary engine comprising a piston-disk cylinder, an abutment-cylinder arranged on the piston-cylinder at right angles thereto, a piston mounted to rotate in the piston-cylinder, an abutment-disk mounted to rotate 100 in the abutment-cylinder, the interior walls of said abutment-cylinder being provided with chambers at the opposite sides of the abutment-disk for receiving steam, and means for causing the abutment-disk and piston-disk to 105 rotate in unison.

3. A rotary engine comprising a piston-disk cylinder, an abutment-cylinder mounted on the piston-disk cylinder at right angles 110 thereto, a piston-disk mounted to rotate in the piston-disk cylinder and of smaller diameter than the interior of the cylinder, a piston-wing carried by the disk for engaging with the inner annular wall of the cylinder, an abutment-disk mounted to rotate in the abutment-cylinder and having an opening at its edge 115 through which said piston-wing may pass, and steam-receiving chambers formed in the walls of the abutment-disk cylinder at opposite sides of said disk, the area of each chamber being equal to the area of the piston-wing. 120

4. In a rotary engine, a rotary piston, an abutment therefor, a valve-seat having a tapered longitudinal opening, a casing in which 125 said valve-seat is fixedly arranged, said valve-seat having a port extended partially around it, a ported valve operating in the valve-seat, blocks movable in said port of the valve-seat, and a regulating-sleeve mounted to move longitudinally on the valve-seat and having means 130

for moving the said blocks circumferentially in said port of the valve-seat.

5. In a rotary engine, a rotary piston, an abutment therefor, a valve-seat, a valve mounted to rotate in said seat, said valve having ports, a casing in which the valve-seat is arranged and having a steam-chest at one end communicating with the interior of the valve, the said valve-seat having an exterior channel 10 or port extended partially around it, cut-off blocks arranged to move in said channel or port, an adjusting-sleeve movable lengthwise of the valve-seat but held from rotary movement thereon, and channels in the interior of 15 said sleeve for receiving projections on the blocks to cause the movements of the blocks

circumferentially of the valve-seat, certain portions of said channels in the sleeve being spirally disposed.

6. A rotary engine having a body divided 20 vertically into four parts, suitably bolted together, the said body having abutment and piston cavities at transverse angles to each other.

In testimony whereof I have signed my name 25 to this specification in the presence of two subscribing witnesses.

WILLIAM BEAUMONT.
